UNITED STATES PATENT OFFICE.

RICHARD H. DANIELS, OF MACON, GEORGIA.

COMBINATION-WRENCH.

SPECIFICATION forming part of Letters Patent No. 583,892, dated June 8, 1897.

Application filed January 19, 1897. Serial No. 619,728. (No model.)

To all whom it may concern:

Be it known that I, RICHARD H. DANIELS, a citizen of the United States, residing at Macon, in the county of Bibb and State of Georgia, have invented certain new and useful Improvements in Combination-Wrenches; and I do hereby declare the following to be a full, clear, and exact description of the invention, such as will enable others skilled in the art to which it appertains to make and use the same.

My invention relates to certain new and useful improvements in combination-tools, the object being to provide a combined pipe wrench, cutter, and threader.

My invention consists of a tool having two movable jaws to clamp about a pipe and serve as a wrench and a combined die-stock and cutter adapted to be clamped by and coacting with said jaws.

My invention also consists of certain novel constructions, combinations, and arrangements of parts, as will be hereinafter described and claimed.

In the accompanying drawings, Figure 1 is a top plan view of the wrench portion of the tool. Fig. 2 is a bottom plan view of the same. Fig. 3 is also a top plan view showing the pipe-cutter applied to the wrench portion. Fig. 4 is a side elevation of the same, showing the jaws of the wrench in section. Fig. 5 is a perspective view of the screw-threading die. Fig. 6 is a perspective view of the wedge-block. Figs. 7, 8, and 9 are views of a modified form of stock and thread-cutter.

The wrench portion of the tool comprises a handle A, having at one end a rigid jaw B, integral therewith and provided with an independent movable jaw B', pivoted at a. The meeting faces b b' of the jaws, at the outer end thereof, are serrated in order to tightly grip a pipe. Between said jaws and the pivoted point the jaws are each formed with a semioval cut-away c', which together form an oval opening for reception of a pipe to be clamped. The serrated faces b b' are intended for gripping small pipes, while the said circular opening is for large pipes. The outer edge d of the fixed jaw on its upper side and the outer edge d' of the movable jaw on its under side are beveled. A stay-bolt e has its inner end pivoted at e' to the said

fixed jaw and its outer end threaded and movable through a guide-block f on the said pivoted jaw, and a set-screw f' on the said threaded end is provided to adjust and hold the jaws tightly clamped about a pipe.

The cutting and die stock is shown in Figs. 3 and 4 and consists of a body or pipe-chamber G, having at one side thereof an opening 60 and a laterally-projecting guideway g, leading therefrom and provided with two vertical side walls and a vertical end wall. The bottom of the guideway adjoining the body-wall has a slot g', and below the guideway is 65 an arm h, provided with a set-screw h', which projects from said body-wall. On the opposite side of the body-wall are two projecting arms i i', the upper or first-named having a set-screw i'.

A sliding tool-carrier block j fits in the vertical guideway g and is moved by means of an adjusting-screw k, which has bearing in the end wall of said guideway. In Fig. 4 an ordinary form of pipe-cutting disk or wheel 70 j' is carried by this tool-block, but the thread-cutting die j'' will be substituted therefor when it is desired to screw-thread a pipe end. A confining-plate l bridges across the front of the guideway and confines the tool-carrier 80 therein. The plate is secured to the guideway-walls by screws l'.

In applying the stock to the wrench portion the jaws of the latter are opened and clamped about the body portion G, as shown 85 in Fig. 4, wherein the movable jaw B' occupies the slot g' and is clamped by the set-screw h', while the fixed arm B has position between the two arms i i' and is clamped by the set-screw i'.

The pipe which is to be cut or threaded is first clamped in a vise and then the tool is applied. The cutter-disk or threading-die is forced against the pipe and the tool operated like an ordinary pipe cutter or threader.

Fig. 2 shows the reverse side of the wrench portion, provided with a diamond-shaped clamping-guide M, which constitutes a part of the cutting-off tool, and N is a curved wedge-block to fill the space between the 90 small diamond clamping-guides and the inner wall of the body portion G. The oval form of the clamping-opening of the wrench is of great importance, for the reason that

when clamping a powerful rolling grip is obtained which does not crush the pipe. The curved wedge-block fills the open space between a circular instrument inserted in the 5 oval clamping-opening and the jaws thereof.

In the modification shown in Figs. 7, 8, and 9 the body B' has an annular die-chamber O, provided with two oppositely-disposed guideways o for the dies p. A lug or pin o' in each 10 guideway is threaded at its upper end and projects through an opening p' in the die. A nut o², fitting on the threaded end of the pin, immovably confines the dies.

Guide-collars K' are provided to fit within 15 the body B' when a small pipe is being operated upon. A side and an end view of one of these collars is shown in Fig. 9. Each collar has a threaded opening q, with which a screw q' on the stock engages.

20 My invention provides a simple and effective form of combination-tool, which may be employed for a variety of purposes.

I do not limit my invention to the precise construction which I have shown in the accompanying drawings merely for illustration.

25 Having thus described my invention, what I claim as new, and desire to secure by Letters Patent, is—

1. In a combination - tool, a handle and 30 wrench portion comprising a handle having at one end thereof a fixed jaw, a movable jaw pivoted to the handle and coacting with the fixed jaw, said two jaws having terminal serrated clamping-faces adapted for small pipes, 35 and between the same and said pivot an opening adapted to receive the body of a pipe cutting or die stock, and means for adjusting the jaws, substantially as described.

2. In a combination - tool, a handle and 40 wrench portion comprising a handle having at one end thereof a fixed jaw, a movable jaw pivoted to the handle and coacting with the fixed jaws, said two jaws having terminal serrated clamping-faces and adapted for small 45 pipes, and between the same and said pivot an opening adapted to receive the body of a pipe cutting or die stock, a stay-bolt pivoted at one end to the said fixed jaw and having a threaded end movable through a guide on the 50 pivoted jaw, and a confining-nut on the said threaded end, substantially as described.

3. In a tool of the class described, the combination of a handle having two clamping-jaws, a pipe cutting or die stock body clamped 55 thereby and provided with a lateral chamber or guideway, and a pipe-cutter or thread-chasing die in said chamber, substantially as described.

4. In a tool of the class described, the com-

bination of a handle having two clamping-jaws, a pipe cutting or die stock body clamped thereby and provided with a side opening and lateral guideway, a pipe cutter or threading die located in said guideway, and a screw to force said cutter or die against the pipe, substantially as described.

5. In a tool of the class described, the combination of a handle having two clamping-jaws, a pipe cutting or die stock clamped thereby and provided with a lateral guideway 60 having a side and an end wall, a pipe cutter or threading die in said guideway, a screw movable in said end wall of the guideway and adapted to force said cutter or die against the pipe, and a plate bridging across and removably secured to the said side walls of the guideway, substantially as described.

6. In a tool of the class described, the combination with a handle having jaws provided with an approximately oval-shaped clamping-opening, of a circular pipe cutter or die stock body clamped therein, and a curved chock-block occupying the vacant space between said jaws and the stock-body, substantially 80 as described.

7. In a tool of the class described, the combination of a handle formed with clamping-jaws, a pipe cutting or die stock body clamped therein, and provided with arms having clamping-screws adapted to engage the said 90 clamping-jaws, and with a lateral guideway for a pipe cutting or threading tool, and adjusting means to force the tool against the pipe, substantially as described.

8. In a tool of the class described, a handle 95 and wrench formed with jaws having an approximately oval-shaped clamping-opening, and a stay-bolt pivoted to one jaw and having a threaded end movable through a guide in the other jaw, and provided on said threaded 100 end with a nut, substantially as described.

9. In a tool of the class described, a handle and wrench formed with jaws having outer serrated clamping-faces for small pipes and an approximately oval - shaped clamping-opening in rear thereof for large pipes, and a stay-bolt pivoted to one jaw and having a threaded end movable through a guide on the other jaw, and provided on said threaded end with a nut, substantially as described.

105 In testimony whereof I have signed this specification in the presence of two subscribing witnesses.

RICHARD H. DANIELS.
